UNITED STATES PATENT OFFICE

155,614

DESIGN FOR A VEHICLE TOP

Virgil G. Klein and Max T. Blue, Wichita, Kans.,
assignors, by direct and mesne assignments, to
Blue Mfg. Co. Inc., Goddard, Kans.

Application March 31, 1947, Serial No. 138,056

Term of patent 14 years

(Cl. D14—3)

To all whom it may concern:

Be it known that we, Virgil G. Klein and Max T. Blue, both citizens of the United States and residing at Wichita, in the county of Sedgwick and State of Kansas, have jointly invented a new, original, and ornamental Design for a Vehicle Top, of which the following is a specification, reference being had to the accompanying drawings, forming a part thereof.

Fig. 1 is a three-quarter front perspective view of a vehicle top embodying the new design.

Fig. 2 is a rear end view of the vehicle top illustrated in Fig. 1.

Fig. 3 is a side elevation of the same vehicle top.

Fig. 4 is a top view of the same vehicle top.

The right hand side of our vehicle top is very similar in appearance to the left hand side shown in Figs. 1 and 3.

The broken lines in Fig. 1 of the drawings are for illustrative purposes only.

We claim:

The ornamental design for a vehicle top, substantially as shown and described.

VIRGIL G. KLEIN.
MAX T. BLUE.
